UNITED STATES PATENT OFFICE.

FRANCIS H. RICHARDS, OF HARTFORD, CONNECTICUT, ASSIGNOR TO ECKLEY B. COXE, OF DRIFTON, PENNSYLVANIA.

TRAVELING-GRAVE FURNACE.

SPECIFICATION forming part of Letters Patent No. 527,454, dated October 16, 1894.

Application filed July 18, 1894. Serial No. 517,875. (No model.)

To all whom it may concern:

Be it known that I, FRANCIS H. RICHARDS, a citizen of the United States, residing at Hartford, in the county of Hartford and State 5 of Connecticut, have invented certain new and useful Improvements in Traveling-Grate Furnaces, of which the following is a specification.

This invention relates to traveling-grate 10 furnaces and is in the nature of an improvement upon the traveling-grate furnace described and claimed in Letters Patent of the United States No. 510,551, granted to me December 12, 1893, to which reference may 15 be had.

The object of my present invention is to provide in connection with a furnace of this class an endless traveling grate of improved construction and organization and to provide 20 means for imparting a traveling movement to the upper and lower runs of the grate in opposite directions, respectively, and whereby the upper and lower runs of the traveling grate will be directly actuated from one end only.

Another object of the invention is to provide means for supporting the traveling grate entirely independent of its actuating mechanism, and also to provide means whereby one or more sections of the traveling grate 25 30 may be removed or replaced without disturbing the continuity of the remaining portion of said grate.

In the drawings accompanying and forming part of this specification, Figure 1 is a 35 sectional side elevation of a traveling-grate furnace embodying my present improvements, portions of the grate-sections being broken away to more clearly show the construction thereof. Fig. 2 is a sectional plan 40 view of a portion of said furnace. Fig. 3 is a sectional side elevation of a portion of the furnace showing a portion of the framework for carrying the grate-mechanism and one of the guide-ways which supports and directs 45 the movement of the traveling grate. Fig. 4 is a vertical cross section of the furnace taken in line *a—a*, Fig. 1 looking toward the left hand in said figure. Fig. 5 is a vertical cross-section of a portion of the furnace taken in 50 line *b—b*, Fig. 1 and looking toward the left hand in said figure, the grate-actuating mech-

anism being partially shown in elevation. Fig. 6 is a side elevation, partially in section, of a portion of the traveling grate, on an enlarged scale, said figure showing two grate-sections in an assembled condition. Fig. 7 is a cross-sectional view of two connected 55 grate-sections taken in line *c—c*, Fig. 8, looking toward the left hand in said figure. Fig. 8 is a vertical longitudinal section of one of 60 the grate-sections.

Similar characters designate like parts in all of the figures.

The furnace in connection with which my present improvements are shown, is, or may 65 be, as to the general construction and arrangement thereof, substantially the same as the one described in Patent No. 510,551 hereinbefore referred to, but it will be understood that my improvements are applicable to other 70 furnaces than the one shown in said patent.

The furnace herein shown has the usual furnace-chamber, *C*, and has the usual inclosing walls at the sides and ends thereof, and is also shown provided with the ordinary roof 75 *A*. The side-walls are designated by 2 and 4, respectively, the front-end wall by 3, the rear-end wall by 5, and the bridge-wall by 7. At the forward end of the furnace this is provided with the usual fuel-hopper, *H*, from 80 which fuel is delivered to the furnace-chamber through the chute or opening, 5', in a well-known manner.

In the form thereof herein shown, the grate which is supported in the furnace-chamber *C*, 85 is in the nature of an endless traveling grate, designated in a general way by *G*, supported for traveling movement in the furnace-chamber *C* and comprising the upper and lower runs, 10 and 11, respectively, the upper run 90 10 constituting the furnace-floor proper.

As a means for supplying air to the fuel at varying pressures at successive points in the length of the furnace-chamber to secure the best practical results in the combustion of 95 the fuel, I have provided an air-blast apparatus which is shown located underneath the upper run of the grate and preferably comprising a series of successive air-blast chambers, herein shown as four in number, and 100 designated by *a*, *b*, *c* and *d*, respectively, which air-blast chambers may be of the same gen-

eral construction and arrangement and carry out the same functions as the air-blast chambers shown and described in Letters Patent of the United States No. 510,588, granted to 5 Eckley B. Coxe December 12, 1893, to which reference may be had, said air-blast apparatus being supported by some suitable connections with the side-walls 2 and 4 of the furnace. These air-blast chambers *a, b, c* and 10 *d* are shown having communicating openings through their division walls and are shown supplied with air from a pipe, *P*, communicating with one of said chambers, herein shown as the chamber *b*, each air-blast chamber having an outlet opening contiguous to the fuel-carrying run of the grate, as will be readily understood by reference to Fig. 1 of the drawings. The mode of operation of supplying air to the fuel at varying pressures at 15 successive points in the traveling movement thereof is substantially the same as described in Letters Patent of the United States No. 499,715, granted to Eckley B. Coxe June 20, 1893, to which reference may be had for a 20 more complete description of the operation of the air-blast apparatus, which air-blast apparatus, broadly, constitutes no part of my 25 present invention.

My present invention particularly resides 30 in an improved construction and organization of traveling grate and in means for supporting, guiding, and actuating said grate, as will be hereinafter more fully described.

In the preferred form thereof herein shown, 35 the traveling grate, which is supported as before described, for traveling movement within the furnace-chamber, consists of a series of transversely-disposed grate-sections, 9, flexibly coupled together by links, 9', at opposite ends thereof, as shown in Figs. 1, 4, 5 and 6, and are preferably provided with rollers, 6, 40 adapted to run upon tracks, as will be hereinafter more fully described.

As a means for supporting the upper and 45 lower runs of the endless grate, and as a means for guiding the successive grate-sections and maintaining them in their proper relative positions during the traveling movement thereof, I have provided grate-supporting 50 guide-ways located one at each side of the furnace-chamber and designated by 20, each of which guide-ways, in the form thereof herein shown, consists of an inner and outer track, 21 and 22, respectively, which are preferably continuous and extend longitudinally 55 of the furnace-chamber as most clearly shown in Fig. 3, said tracks 21 and 22, forming, between them, a continuous channel or guide-way, 20, adapted for receiving the rollers 6 60 of the grate-sections 9. The upper portion of the channel 20, or that portion which directs the movement of the fuel-carrying run 10 of the grate, is herein shown in a horizontal plane, while the lower portion of said 65 channel, or that portion which directs the movement of the lower run of the grate, is shown inclined upward toward its rear end so

that the upper and lower runs of the grate at that end nearest the rear end of the furnace-chamber will be in closer proximity than 70 at the forward or fuel-receiving end thereof when in operative position, thus securing a shorter turn to the endless grate at its delivering end than at its receiving end.

In practice, the guide-ways will preferably 75 be formed integral with the side-plates 23 and 23' of the furnace-chamber, said side-plates being laterally flanged as most clearly shown in Fig. 5 to form the tracks 21 and 22 which practically constitute said guide-ways. 80

To provide for the ready removal of one or more of the grate-sections, a portion of the tracks 21 and 22, at the forward end of the furnace-chamber are shown formed separate from the remaining portions of said tracks, 85 said segments of tracks being formed upon a removable portion, 25, of the side-plates 23 and 23', respectively, one only of which is clearly shown. (See Fig. 3 of the drawings.) By removing the track-segments 25 at each 90 side of the furnace-chamber I am enabled to disconnect a grate-section from the next adjacent section and withdraw the same from either side of the furnace, as will be readily understood by reference to said Fig. 3 of the 95 drawings.

In the present instance I have shown the furnace provided with a water-seal substantially such as described in the Patent No. 510,588, hereinbefore referred to, the function 100 of which is to prevent the possible escape of air from the air-chambers around the lower run of the traveling grate.

In the form thereof herein shown, each 105 grate-section consists of a perforated fuel-supporting plate, 26, having transverse flanges, 27, at opposite ends thereof, and having a longitudinal central web or flange, 28, extending from end to end of the grate-section between the end-flanges 27 thereof. In 110 practice the central longitudinal flange 28 will be reinforced at opposite sides at each end thereof, and will be inwardly tapered to form a tooth, 29, at each end of the grate-section adapted to be engaged by the teeth 115 of a revolute driver, 12, as will be herein-after more fully described. Formed at each 120 end of the grate-section, preferably integral with the transverse flanges 27, are two remotely-disposed trunnions, 30, whose axes 125 are in a line, preferably, parallel with relation to the fuel-supporting face of the grate-section, each of which trunnions is adapted to be removably-engaged by the end of a link, 9', as shown most clearly in Fig. 6 of 130 the drawings. Loosely mounted upon pins, 8, secured in the trunnions 30 are the rollers 6 which ride upon the tracks 21 and 22 of the guide-ways, as will be seen by reference to Figs. 5 and 8 of the drawings. The pins 135 which carry the rollers 6 will, in practice, be fixed in their respective trunnions by being cast-welded therein. The trunnions 30 at each end of each grate-section will, in prac-

tice, be cross-sectionally angular, they being shown concentric to the axis of the roller-pins 8 at their inner sides to coincide with the semi-circular ends of the links in engagement therewith, whereas the opposite sides thereof are shown of angular formation, the under sides, as at 31, being preferably parallel to the bottom edge of the end-flanges 27 of the grate-section, and the outer sides, as at 32, 5 being inclined-downward toward the opposite sides of said section. This cross-sectionally angular construction of trunnion is of material importance as it not only provides a free pivotal connection between the coupling link 9' and trunnion, but also provides abutments or stop-faces for said coupling-link, which faces, while they permit the necessary amount of lateral movement of said links, limit the movement thereof during the change 10 in positions of successive grate-sections during their circuitous traveling movement and thus retain the grate-sections in the proper relative positions. The coupling links 9' will, in practice, usually be made of flat bar-metal formed into a continuous loop as shown 15 in Fig. 6 of the drawings, thus forming an oblong link having semi-circular trunnion-engaging ends, said ends being adapted for engaging the opposite curved faces of two trunnions of two adjacent grate-sections, respectively, as will be understood by reference 20 to Figs. 1 and 6 of the drawings.

As a means for imparting a traveling movement to the upper and lower runs of the grate in opposite directions, respectively, I have provided two revolute drivers, 12, which in the form thereof herein shown are in the nature of wheels having peripheral teeth, 12', adapted for engaging within the tooth-spaces 25 between the successive teeth 29 of the successive grate-sections 9. These revolute drivers are both shown mounted upon a single shaft, 13, at each end thereof, said shaft being journaled in bearings on the side-plates 23 and 23' of the furnace-chamber and being provided at one end thereof with a worm-wheel, 40, the teeth of which are in engagement with the teeth of a worm, 41, upon a driving-shaft, 42, journaled in bearings, 43, 30 upon the side-wall 4 of the furnace, this driving shaft 42 being provided with a pulley, 44, by means of which it is driven by a belt (not shown) from any suitable source of power.

By providing each grate-section with a tooth at each end thereof midway of the width of said section, as hereinbefore described, and by providing a revolute driver with teeth of less width than the length of the tooth-spaces between the teeth of adjacent grate-sections, there is a resultant gain 35 in the length of the endless grate over the tooth-space distances of the driver which allows for any variation in widths of the grate-sections, and also insures a free intermeshing engagement of the teeth of the driver with the teeth of the grate-sections during their constantly changing positions while

traveling around the forward side of the driver, as will be readily apparent by reference to Fig. 1 of the drawings, which partially 40 illustrates in section, the successive positions of the grate-sections and their teeth relative to the teeth of the revolute driver.

By the construction and organization herein shown and described, it will be seen that the 45 grate-sections, owing to the position of their respective teeth and their loose connections with the successive grate-sections are free to rock laterally as is necessary in passing around the forward end of their circuit, and 50 that, by the use of the rollers, will have a free traveling movement without undue retarding friction.

Having thus described my invention, I 55 claim—

1. In a furnace of the class specified, the combination with the furnace-chamber and its inclosing walls, of an endless grate supported for traveling movement within the furnace-chamber and comprising a series of 60 transversely-disposed grate-sections, each of which has two trunnions at each end thereof having curved inner faces and angular outer faces, substantially as described, rollers carried upon pins concentric to the curved portions of said trunnions, loop-shaped coupling-links in engagement with the curved faces of adjacent trunnions of adjacent grate-sections and adapted for engaging the angular faces of said trunnions during the circuitous 65 traveling movement of the grate to limit the lateral movement of said sections relatively to each other, and means for imparting a traveling movement to the endless grate, substantially as described. 70

2. In a furnace of the class specified, the combination with the furnace-chamber and its inclosing-walls, of grate-supporting guide-ways at opposite sides of the furnace-chamber, and an endless grate supported for traveling movement by said guide-ways within the furnace-chamber, and comprising a series of transversely-disposed grate-sections, each of which has two trunnions at each end thereof, which trunnions have curved inner 75 faces and angular outer faces, substantially as described, and loop-shaped coupling-links in engagement with the curved faces of adjacent trunnions of adjacent grate-sections, substantially as described and for the purpose set forth. 80

3. In a furnace of the class specified, the combination with the furnace-chamber and its inclosing walls, of an endless grate supported for traveling movement in guide-ways 85 secured to the side-walls of the furnace-chamber, and comprising a series of coupling-link-connected grate-sections having internal teeth at opposite ends thereof and carrying rollers at said opposite ends which are supported in said guide-ways, drivers located at one end of the furnace-chamber and engaging the teeth of and imparting a traveling movement to the grate-sections, and means 90

for rotating said drivers, substantially as described and for the purpose set forth.

4. In a furnace of the class specified, the combination with the furnace-chamber and its inclosing walls, of an endless grate supported for traveling movement within the furnace-chamber and comprising an upper and a lower run and consisting of a series of transversely-disposed coupling-link-connected grate-sections having air-supply openings through the fuel-supporting portions thereof, and supported for traveling movement by rollers at each end thereof running in guide-ways connected with the side-walls of the furnace-chamber, driving mechanism located between the upper and lower runs of the traveling grate at one end thereof and adapted for imparting a traveling movement to said grate, and an air-blast apparatus located intermediate to the upper and lower runs of said grate and adapted for supplying air through the openings in the grate-sections to the fuel supported upon the upper run, substantially as described and for the purpose set forth.

5. In a furnace of the class specified, an endless grate supported for traveling movement within the furnace-chamber and comprising a series of longitudinally-flanged grate-sections having two trunnions at each end thereof having curved inner faces and angular outer faces substantially as described, rollers carried upon pins concentric to the curved portions of said trunnions, and loop-shaped coupling links in engagement with the curved faces of the adjacent trunnions of adjacent grate-sections and adapted for engaging the angular faces of said trunnions during the circuitous traveling movement of the grate, and means for imparting a traveling movement to the endless grate, substantially as described.

6. The herein-described grate-section for endless grates of the class specified, it consisting of a perforated fuel-supporting plate having a longitudinal central rib extending from end to end thereof and reinforced at opposite ends to form a driving tooth at opposite ends thereof, two cross-sectionally angular trunnions at each end of the grate-section adapted to be engaged by coupling-links, and rollers revolvably carried upon pins secured in said trunnions, substantially as described and for the purpose set forth.

55. 7. In a furnace of the class specified, the combination with the furnace-chamber and its inclosing walls, of a pair of coinciding circuitous grate-supporting guide-ways located one at each side of the furnace-chamber, an endless grate supported for traveling movement in said guide-ways and comprising a series of coupling-link-connected grate-sections carrying rollers at opposite ends thereof which are supported by said guide-ways and having one centrally-disposed tooth at each end adapted for engagement by the teeth of a revolute driver, revolute drivers located

at one end of the endless grate and engaging the teeth of, and imparting a traveling movement to, the grate-sections, and means for rotating said drivers, substantially as described and for the purpose set forth.

8. In a furnace of the class specified, the combination with the furnace-chamber and its inclosing walls, of two circuitous grate-supporting tracks located one at each side of the furnace-chamber, an endless traveling grate having an upper and lower run supported for traveling movement in opposite directions between said tracks and comprising a series of perforated grate-sections each having two cross-sectionally angular trunnions at each end thereof, coupling-links extending over the adjacent trunnions of and connecting adjacent grate-sections so as to permit a limited amount of lateral movement of said sections relatively to each other, and rollers carried at the ends of said trunnions and riding upon said tracks, means in connection with and adapted for imparting a traveling movement to the upper and lower runs of the grate in opposite directions, respectively, and an air-supply apparatus located between the upper and lower runs of the grate and adapted for supplying air through the perforations in the grate-sections to the fuel carried upon the upper run of said grate at varying pressures at successive points in the length of the furnace-chamber, substantially as described.

9. In a furnace of the class specified, the combination with the furnace-chamber and its inclosing walls, of two circuitous grate-supporting tracks formed integral with the side-plates of the furnace-chamber and having at one end thereof a removable section, an endless traveling grate supported for traveling movement by said tracks and comprising a series of grate-sections having trunnions connected together by coupling-links and having rollers at opposite ends thereof supported between the tracks, substantially as described, and actuating mechanism for said grate, substantially as and for the purpose set forth.

10. The herein-described grate-section for traveling grates of furnaces of the class specified, it consisting of a perforated fuel-supporting plate having transverse flanges at the opposite ends thereof and having two cross-sectionally angular trunnions at each end thereof, each trunnion of which has a curved inner face and angular outer faces or abutments, the curved face of which trunnions constitutes a pivot-bearing for a coupling-link and the angular faces of which trunnions constitute abutments for limiting the lateral movement of said section relatively to the coupling-link, pins fixed in said trunnions, and rollers carried upon said pins at the outer ends thereof remote from the ends of said section, substantially as described and for the purpose set forth.

11. In a furnace of the class specified, the

combination with the furnace-chamber and its inclosing walls, of the two side-plates 23 and 23' each having a circuitous grate-supporting guide-way, a section of which is formed integral with a removable portion of said side-plate, an endless grate supported for traveling movement by rollers at opposite sides thereof engaging the two guide-ways and comprising a series of transversely-disposed grate-sections connected together for

lateral movement by coupling links engaging trunnions of said sections intermediate to the rollers and ends of said sections, and means for imparting a traveling movement to the grate, substantially as described.

FRANCIS H. RICHARDS.
